DESIGN FOR A CONTOUR MEASURING PROJECTOR

Henry F. Kurtz, Rochester, N. Y., assignor to
Bausch & Lomb Optical Company, Rochester,
N. Y., a corporation of New York

Application August 20, 1938, Serial No. 79,483

Term of patent 14 years

To all whom it may concern:

Be it known that I, Henry F. Kurtz, a citizen of the United States and a resident of Rochester, county of Monroe, and State of New York, have invented a new, original, and ornamental Design for a Contour Measuring Projector, of which the following is a specification, reference being had to the accompanying drawing, forming a part thereof.

The figure is a perspective view of a contour measuring projector embodying my new design.

I claim:

The ornamental design for a contour measuring projector, substantially as shown.

HENRY F. KURTZ.
